UNITED STATES PATENT OFFICE.

OTIS D. RICE, OF WINTHROP, MASSACHUSETTS.

DRYING APPARATUS.

Application filed March 15, 1922. Serial No. 543,937.

To all whom it may concern:

Be it known that I, OTIS D. RICE, a citizen of the United States, and resident of Winthrop, county of Suffolk, State of Massachusetts, have invented an Improvement in Drying Apparatus, of which the following description, in connection with the accompanying drawing, is a specification, like characters on the drawing representing like parts.

This invention relates to drying apparatus of that type comprising a drying chamber to contain the material to be dried, and arranged to provide a closed circuit, means to cause a current of drying medium to circulate continuously through said closed circuit and over the material to be dried, and means to maintain a reduced pressure in said drying chamber. A drying apparatus of this type is illustrated and described in my Patent No. 1,328,897, Jan. 27, 1920.

The object of the present invention is to provide a drying apparatus of the above-mentioned type which can be used to dry material in the form of a continuous web or sheet by feeding the web or sheet through said chamber. To feed the web into the chamber involves the provision of an inlet opening or passage leading to the chamber and through which the web passes, and the delivering of the web from the chamber involves the provision of another opening or passage leading from the chamber and through which the web is discharged.

Another object of my invention is to provide a drying apparatus such as above described with means for reducing to the minimum the leakage of air through the inlet and outlet openings and doing this in such a way as to avoid any possible injury to the web material passing through said openings, thus providing a drying apparatus which is suitable for drying web material in the form of paper or cloth.

In order to give an understanding of the invention I have illustrated in the drawings a selected embodiment thereof which will now be described after which the novel features will be pointed out in the appended claims.

In the drawings, Fig. 1 is a longitudinal sectional view showing more or less diagrammatically a drying apparatus embodying my invention.

Fig. 2 is a section on the line 2—2, Fig. 1. Fig. 3 is a section on the line 3—3, Fig. 1.

Fig. 4 is an enlarged sectional view taken through one pair of baffles.

Fig. 5 is a front view of Fig. 4.

In the drawings 1 indicates a drying chamber in which the material is to be dried and which is constructed so that the drying medium may circulate therein continuously through a closed circuit, and also constructed so that a reduced pressure may be continuously maintained therein. In the device herein shown the chamber 1 is divided by partitions 2 into a plurality of compartments indicated at 3 and each compartment is constructed to constitute a closed circuit through which a heating or drying medium may be continuously circulated. These compartments are shown as communicating with each other through openings 4 formed in the partitions, and 5 indicates the web material which is to be dried, said material extending across each compartment and passing through the openings 4 therein. 6 designates suitable rolls which serve to guide the web material.

The web material 5 thus divides each compartment into two passages 8 and 9, one above and the other below the web material, said passages communicating with each other at the ends 7 of the compartments. The passages 8 and 9 communicating at their ends thus form a closed circuit in each compartment through which a heating or drying medium may be continuously circulated as indicated by the arrows in Fig. 3. This circulation may be caused in any suitable way, as by means of fans 10 which are indicated somewhat diagrammatically and which may be driven in any usual manner.

11 indicates heaters over which the drying medium circulates, said heaters being for the purpose of heating the medium to increase its heating or drying efficiency.

Means are provided for maintaining a reduced pressure in each compartment and this may be done by connecting the compartment with one or more suction pipes 12 which lead to a suction apparatus or exhaust device. These suction pipes 12 will preferably be located at the position in the closed circuit where the circulating medium is coolest, which will usually be in just advance of the heater 11.

With this apparatus as thus far described, the suction apparatus, not shown, will maintain continuously a reduced pressure in each compartment and at the same time the drying medium in each compart-

ment will be continuously circulated therein through a closed circuit and will thus be repeatedly brought in contact with the web material to be dried.

5 The operation of the apparatus as thus far described is substantially the same as that set forth in my above-mentioned Patent No. 1,328,897.

10 One feature of my present invention relates to a construction whereby the web material may be continuously fed into the drying chamber 1 and subjected progressively to the drying action therein, and also to means for reducing to a negligible quantity the leakage of air through the inlet opening or passage through which the web is introduced into the drying chamber.

20 Another feature of the invention relates to a construction whereby the web material may be continuously withdrawn from the drying chamber, and also to means for reducing to a negligible amount the leakage of air into the chamber through the discharge opening.

25 In the construction herein shown the web 5 is introduced into the chamber 1 through an inlet passage 13, and this passage is provided with means for progressively decreasing the pressure from the outer end 30 thereof at which the web enters to the inner end thereof at which the web is delivered from said passage into the chamber so that at the delivery end the pressure in the passage will vary but little from that in the 35 drying chamber 1.

The drying chamber 1 is also provided with another elongated passage 14 through which the web material is delivered from the drying chamber, and this passage 14 is 40 also provided with means for progressively decreasing the pressure therein from the outer end at which the web is delivered, to the inner end which communicates with the chamber and at which the web enters the passage 14.

45 This progressive change of pressure in the passages 13 and 14 is herein provided for by employing in each passage a plurality of baffles which divide the passage into separate compartments that, however, communicate with each other through a restricted opening of sufficient width to permit the web to pass. With this arrangement the pressure in the compartments will be progressively decreased from the outer compartment to the inner compartment, and in the inner compartment the pressure will be only slightly greater than that in the drying chamber. Owing to this slight difference of 55 pressure between the chamber and the inner compartment and between the adjacent compartments there will be a relatively small leakage of air through the compartments into the drying chamber, said leakage being so small as not to counteract the action of

the suction apparatus in maintaining the desired reduced pressure.

These baffles are also constructed so that the web material may pass between them without contacting therewith and thus without being injured thereby.

Extending transversely across the passage 13 both above and below the web 4 are partitions 15. Each partition has secured thereto a flexible baffle plate, the baffle plates secured to the lower partitions being indicated at 16 and those secured to the upper partitions being indicated at 17. These baffle plates are arranged in pairs, each pair comprising a baffle plate above and one below 80 the web 5, and the baffles of each pair converging toward each other to form a relatively narrow throat 18 through which the web 5 passes. The throat has a width slightly greater than the thickness of the 85 web 5 so that the latter may pass therethrough without contacting with the baffles.

Means are also preferably provided for adjusting the baffles toward and from each other to accommodate webs of different thickness. One way of accomplishing this is shown in Figs. 4 and 5, wherein the baffle 16 is curved backwardly beyond the throat and the edge 19 thereof is secured to a plate 20 extending across the passage 13, and the baffle 17 is similarly curved away from the throat as shown at 21 and is secured to a bar or plate 22 extending across the passage 13. The bar 20 has at each end a lug 23 into which is screw-threaded an adjusting screw 24, the latter having a reduced upper end 25 which extends through an opening in a lug 26 extending from the plate 22. The upper end of the adjusting screw 24 is formed with a collar 27 and a spring 28 encircles the reduced portion 25 and is confined between the collar 27 and the lug 26. The adjusting screw having this construction will have a shoulder 29 which seats against the under side of the lug 26 and the spring 28 will yieldingly hold the screw in this position. By turning the adjusting screw the lower screw-threaded end thereof will be screwed up or down in the lug 23, thus adjusting the width of the throat 18.

55 A similar construction is employed in the discharge passage 14.

It will, therefore, be seen that each of the passages 13 and 14 is divided into separate compartments which communicate with each other through the restricted throat 18, and that the web material passes through said compartments and throats successively.

60 In the operation of the device the pressure difference between the chamber 1 and the atmosphere will be divided between the separate compartments in the inlet and outlet passages, the pressure in the compartments varying progressively from the outer to the inner end of the passage. The pres-

sure in the compartment adjacent the inner end will be lowest and will be slightly above that in the drying chamber and the pressure in the compartment at the outer end of the 5 passage will be greatest and will be slightly below atmospheric pressure. There will, of course, be a slight leakage from one compartment to the other and into the drying chamber but the total leakage into the drying 10 chamber will be only that which is due to the difference of the pressure between the innermost compartment of each passage and that of the drying chamber.

In fact the leakage through any throat 15 18 will be determined by the difference in the pressure on opposite sides of the corresponding baffles.

The leakage of air through the throats 18 has the effect of floating the web through the 20 throat between two air films, and the presence of these air films protect the web from contact with the baffles.

The deflector plates 30 are shown and which may be used if desired and which 25 serve as means to deflect the air currents against the web.

The springs 28 have the advantage that they provide yielding throats, which yield or open to permit a thick spot in the web 30 to pass without breaking the web.

While I have herein illustrated a selected embodiment thereof I do not wish to be limited to the constructional features shown.

I claim.

35 1. In a drying apparatus of the type having a drying chamber, means to cause the drying medium to circulate therein through a closed circuit, and means to maintain vacuum conditions in said chamber, the combination with a drying chamber having an inlet passage leading thereto, of means to feed web material into the chamber through said passage, and means to reduce progressively the pressure from the outer to the inner end 40 of the passage.

45 2. In a drying apparatus of the type having a drying chamber, means to cause the drying medium to circulate therein through a closed circuit, and means to maintain vacuum conditions in the chamber, the combination with a drying chamber having an inlet passage leading thereto, of means to feed web material into the chamber through said passage, and means dividing said passage into a plurality of compartments which communicate with each other and through which the web passes, whereby the pressure is reduced progressively from the outer to the inner end of the passage.

50 3. In a drying apparatus of the type having a drying chamber, means to cause the drying medium to circulate therein through a closed circuit, and means to maintain vacuum conditions in the chamber, the combination with a drying chamber having an in-

let passage leading thereto, of means to feed web material into the chamber through said passage, and means dividing the passage into a plurality of communicating compartments through which the web passes, the communication between adjacent compartments being in the form of a narrow slit slightly wider than the thickness of the web passing therethrough, whereby the pressure is reduced progressively from the outer to 75 the inner end of the passage.

4. In a drying apparatus of the type having a drying chamber, means to cause the drying medium to circulate therein through a closed circuit, and means to maintain vacuum conditions in the chamber, the combination with a drying chamber, of an inlet passage leading thereto, of means to feed web into the chamber through said passage, and means dividing the passage into a plurality of communicating compartments through which the web passes, the communication between one compartment and the next being in the form of a converging throat which is slightly wider at its narrowest point than the thickness of the web passing therethrough, whereby the pressure is reduced progressively from the outer to 80 85 90 the inner end of the passage.

5. In a drying apparatus of the type having a drying chamber, means to cause the drying medium to circulate therein through a closed circuit, and means to maintain vacuum conditions in the chamber, the combination with a drying chamber having an inlet passage leading thereto, of means to feed web into the chamber through said passage, and means dividing the passage into a plurality of communicating compartments through which the web passes, the communication between one compartment and the next being in the form of a converging throat which is slightly wider at its narrowest point than the thickness of the web passing therethrough, and means to adjust 95 100 105 the width of each throat, whereby the pressure is reduced progressively from the outer to the inner end of the passage.

6. In a drying apparatus of the type having a drying chamber and means to maintain vacuum conditions therein, the combination with a drying chamber having a delivery passage leading therefrom, of means to deliver web material from said chamber through said passage, and means dividing said passage into a plurality of communicating compartments through which the web passes, whereby the pressure is reduced progressively from the outer to the inner end of 110 115 120 the passage.

7. In a drying apparatus of the type having a drying chamber and means to maintain vacuum conditions therein, the combination with a drying chamber having a delivery passage leading therefrom, of means

to deliver web material from said chamber through said passage, and means dividing said passage into a plurality of communicating compartments through which the web passes, each compartment communicating with the adjacent compartment through a converging throat of a width slightly wider than the thickness of the web, whereby the pressure is reduced progressively from the outer to the inner end of the passage.

8. In a drying apparatus of the type having a drying chamber and means to maintain vacuum conditions therein, the combination with a drying chamber having an in-

let passage leading thereto, and a delivery passage leading therefrom, means to feed web material through the inlet passage through the chamber and through the delivery passage, and means in each passage dividing it into a plurality of compartments which communicate with each other by means of a narrow throat through which the web passes, whereby the pressure is reduced progressively from the outer to the inner end of the passage.

In testimony whereof, I have signed my name to this specification.

OTIS D. RICE.
